BALL COCK FLOAT

Adolf Schoepe, 1620 N. Raymond Ave., Fullerton, Calif.
92631, and Frederic E. Schmuck, 535 Century Drive,
Anaheim, Calif. 92805

Filed Jan. 2, 1974, Ser. No. 429,721

Term of patent 14 years

Int. Cl. D23—01

U.S. Cl. D23—33

Fig. 1.

Fig. 2.

Fig. 3.

Fig. 5.

Fig. 4.

Fig. 6.

FIG. 1 is a side elevational view of a ball cock float showing our new design;

FIG. 2 is a top plan view;

FIG. 3 is a right-end elevational view;

FIG. 4 is a left-end elevational view;

FIG. 5 is a bottom plan view; and

FIG. 6 is a bottom perspective view.

The broken line representation of a guide and valve connecting link in FIG. 1 are for purposes of illustration only.

We claim:

The ornamental design for a ball cock float, as shown and described.
